UNITED STATES PATENT OFFICE.

ETIENNE BOILEAU, OF ST. LOUIS, MISSOURI, ASSIGNOR OF ONE-HALF TO
WILLIAM SOMERVILLE, OF SAME PLACE.

LAMP-BURNER.

SPECIFICATION forming part of Letters Patent No. 258,010, dated May 16, 1882.

Application filed January 16, 1882. (No model.)

To all whom it may concern:

Be it known that I, ETIENNE BOILEAU, of the city of St. Louis, in the State of Missouri, have invented a certain new and useful Improvement in Wick-Raisers for Lamp-Burners, of which the following is a specification, reference being had to the accompanying drawings, forming part of the same.

My improvement relates to an efficient device for raising and lowering the wick in an Argand burner by means of two spring-claws attached to a vertically-sliding ring and operated by a cam turned by the chimney-holder.

In the drawings, Figure 1 is a perspective view of the burner. Fig. 2 is a view of the same partly in vertical section at 2 2, Fig. 5, and partly in side elevation. Fig. 3 is a similar view, partly in section at 2 2, with the flange-cam turned in position to bring the parts marked by broken line 3 3 into the plane of the section 2 2. Fig. 4 is a side view of part of the outer wick-tube. Fig. 5 is a horizontal section at 5 5, Fig. 2. Fig. 6 is a horizontal section at 6 6, Fig. 3. Fig. 7 is a side view of the cam-flange. Fig. 8 is a perspective view of the claw-ring. Fig. 9 is an under perspective view of the cam-ring and cam and the wick-raising claws and ring to which they are connected.

The burner has a base, A, whose neck *a* screws into the lamp-reservoir, as usual.

B is the outer wick-tube, attached at the lower end to the neck *a*.

C is the inner wick-tube, secured concentrically in the tube B by a rib, D. (See Figs. 5 and 6.) Through the sides of the tubes B C and through the rib D is formed an opening, D', for the entrance of air into the interior tube, C, for the supply of air at the inside of the circular frame.

E is the wick filling the annular space between the tubes B and C. The tube B has vertical slots *b*, through which the teeth *f* of the claws *F* pass to engage the wick. The claws *F* have each two vertical series of teeth to take a firm hold of the wick.

I am aware that lifting-claws have been before made with a horizontal series of teeth; but the engagement of the teeth upon the wick is somewhat uncertain, as all of the teeth

are liable to come in contact with a single "filling-thread" of the wick and force the wick a little distance upward or downward in entering between the threads, so that the claws of the two sides do not maintain uniformity of action, and the wick is raised unevenly and becomes jammed in its annular socket.

The outer sides, *b'*, of the slots *b* are turned out in flanges, forming upon the outer side guides for the ring *G*, to which the claws are connected, and upon the inner side guides to the claws, preventing their lateral displacement when disengaged from the wick. The claws *F* are connected to the ring *G* by springs *H*, which tend to hold the teeth of the claws out of engagement with the wick.

h are notched studs projecting from each of the springs *H* and embracing the edge of the flange-cam *I*, to give to the ring *G* and claws *F* their vertical movement and to the latter their inward and outward movement. The cam *I* projects inwardly from the turning-ring *J*, which is turned by the chimney-holder *K* by means of projections *j* and *k* upon the two rings *J* and *K*, respectively, (said ribs or projections engaging each other.) The flange-cam *I* has two broad parts or portions, *i*, which force the claws into the wick, (see Figs. 3, 5, 7,) such portions having inclination to move the claws and ring *G* vertically while the claws are in engagement with the wick. At *i'* (see Figs. 2, 5, 7) the flange is so narrow that the claws are allowed to move outward under the influence of the springs *H*, so that their teeth are out of engagement with the wick. The parts *i'* are inclined in an opposite direction to the parts *i*, so that in the continued rotation of the ring *J* the parts *i* and *i'* impart to the claws an alternate ascending and descending motion, raising or lowering the wick by a series of intermittent movements, according to the direction in which the parts are turned. Between the vertically-inclined parts *i* *i'* of the cam are horizontal parts *i*², whose edges are inclined in such a manner as to force the claws *F* toward the wick, or to allow them to spring outward therefrom under influence of the springs *H*. Thus it will be seen that when the claws are moving inward and outward to and from the wick they have

no vertical movement, so that the movements of the parts are positive and regular, and this insures the regular movement of the wick.

I have shown the claws F connected to the ring G by flat springs H; but the springs H may be made of wire, and the forks h may be made by bending the wire in a suitable manner. The lateral movement of the claws when in their outer position would be restrained by the flanges b'.

I claim as my invention—

A lamp-burner having a vertically-sliding ring with spring-claws having notched studs connected thereto, and the cam I with inclined portions i and i', constructed and operating substantially as set forth.

ETIENNE BOILEAU.
